United States Patent Office

Des. 195,575
Patented July 2, 1963

195,575

COMBINED TABLE AND VALET STAND OR SIMILAR ARTICLE

Harold Gleitsman, New Rochelle, and Carl Fuerst, Bronx,
N.Y., and John H. Squadra, Westport, Conn., assignors to Gleitsman's, Inc., Long Island City, N.Y., a corporation of New York

Filed Jan. 7, 1963, Ser. No. 73,080

Term of patent 14 years

(Cl. D33—14)

FIG. 1

FIG. 2

FIG. 3

FIG. 1 is a front perspective view of the combined table and valet stand showing our design;

FIG. 2 is a front elevational view, on a reduced scale;

FIG. 3 is a side elevational view, on a reduced scale;

FIG. 4 is a bottom view, on a reduced scale; and

FIG. 5 is a top view, on a reduced scale.

We claim:

The ornamental design for a combined table and valet stand or similar article, substantially as shown.
